TONOMETER

Ulrich Ollendorff, New York, N. Y.

Application March 21, 1944, Serial No. 527,452

13 Claims. (Cl. 73—80)

This invention is a novel improvement in tonometers for measuring the tension of eyeballs, i. e., their softness or hardness, and the principal object of the invention is to provide a tonometer adapted to be used preferably, but not necessarily, in a horizontal position on a patient in a sitting position as distinguished from tonometers heretofore used in which the instrument disposed vertically could be used on a patient when lying only on his back.

Another object of the invention is to provide a tonometer having a novel arrangement of counterbalance weights and levers, one being applied to balance the pointer, and another being applied to regulate the pressure of force in applying the instrument to the eyeball at the moment of reading or measurement, the provision of the weights and levers replacing what in former vertical measuring tonometers was effected by gravity.

I will explain the invention with reference to the accompanying drawing which illustrates one practical embodiment thereof to enable others familiar with the art to adopt and use the same; and will summarize in the claims, the novel features of construction, and novel combinations of parts for which protection is desired.

In said drawing—

Fig. 1 is a front elevation of the tonometer, partly in section.

Fig. 2 is a bottom plan view of the tonometer shown in Fig. 1.

Fig. 3 is a transverse section on the line 3—3, Fig. 1.

Fig. 4 is a perspective view of one of the weights.

As shown, my novel tonometer comprises a plate 1 carrying an arcuate head 1a provided with a calibrated scale 2, plate 1 having an open frame or yoke 3 at its end opposite from the scale 2. Frame 3 is provided with a collar 4 retaining a fixed sleeve 5 therein by means of a pin 6, the axis of sleeve 5 being disposed axially of plate 1.

On plate 1 adjacent yoke 3 but offset above the axis of sleeve 5 is a bearing 1b (preferably antifriction) for a pivot 7 carrying a pointer 8 secured thereto as at 9, said pointer 8 cooperating with scale 2. Pivot 7 also carries a depending arm 7a crossing the axis of sleeve 5, as shown, said arm 7a having at its lower end a downwardly and outwardly inclined counterbalancing lever 10 which is threaded and which carries an adjustable weight 11 which may be adjusted or shifted thereon to cause the pointer to gravitationally overlie a fixed point 2x or graduation of scale 2, or to gravitationally assume any other position, when the tonometer is held horizontally, i. e., in

the position shown in Fig. 1, and when the lever 7a is not subjected to a force other than gravity.

Slidably mounted within the bore of sleeve 5 is a pin 13 having a slightly enlarged head 13a at its outer end within the frame or yoke 3 adapted to contact the arm 7a of pointer 8, the pivot 7 of the pointer 8 being offset from the axis of pin 13 as hereinbefore stated. The blunted inner end of pin 13 extends beyond the inner end of sleeve 5, as at 13b, and the adjacent end of sleeve 5 is provided with a disk-like enlargement 5b having a concave face 5c adapted to receive and conform with the shape of the eyeball of the patient.

On the underside of sleeve 5 disposed intermediate the collar 4 and enlargement 5b is a key 5a, and slidably mounted upon the sleeve 5 between the inner end of key 5a and the collar 4 is slidably mounted a bushing 12 having a keyway 12a therein, as shown in Figs. 1 and 3, which keyway 12a is deeper at the inner end of the bushing than at the outer end, the bottom of keyway 12a being thus slightly tapered as shown. Attached to the outer end of bushing 12 are handles 12b adapted to be held by the operator's hand to support the instrument and at the same time to provide means for the sliding of the bushing 12 on sleeve 5.

In order to control the pressure at which the instrument is applied to the eyeball, I provide an inwardly and downwardly inclined lever 14 pivoted, as at 14a, to the inner end of key 5a of the sleeve, said lever having a flattened face or portion 14b adjacent the pivot 14a engaging the underside of sleeve 5 to gravitationally maintain the lever 14 at an angle of about 30° to the axis of sleeve 5 as shown in Fig. 1. Lever 14 is threaded and carries an adjustable weight 15 which as shown more particularly in Fig. 4 has an arcuate recess 15a in its periphery adapted to conform with the curvature of the underside of sleeve 5, and which will permit the lever 14 to be swung upwardly when engaged by the inner end of bushing 12. On lever 14 is a mark 14x for the purpose hereinafter described.

In operation, before using the tonometer, the same is placed against a convex metallic test piece T shown in dotted lines in Fig. 1, which piece T conforms with the shape of the concave face 5c of the disk-like enlargement 5b, and the weight 11 adjusted so that the pointer indicates "0." Normal eye pressure then will permit the pointer when in actual use to shift into position "3." The tonometer in the preferred use thereof is then held in a horizontal position with the

concave face 5c of the disk-like enlargement 5b just touching the anaesthetized eyeball of the patient with eyelids spread apart and when the patient is in a sitting position, and with the sleeve 12 out of contact with the lever 14. At the moment of contact the pin 13 will start to move outwardly according to the intraocular pressure of the eyeball, the movement of pin 13 being directly transmitted to lever 1a which operates the pointer 8 and the pointer 8 will then start to rise on the scale 2. The balance of the pointer 8 will be effected by the weight 11 on the inclined lever 10 carried by arm 1a, and if desired the weight thereon may be increased by placing additional weights 11 on lever 10 or by mere adjustment of the single weight 11 along said lever. The bushing 12 will then be moved inwardly on sleeve 5 by shifting handles 12b in the direction of the eye of the patient, which movement will tend to likewise move the enlargement 5b into firmer contact with the eyeball due to friction between the parts 12 and 5. Such movement of bushing 12 will cause the inner slotted end of bushing 12 opposite keyway 12a to contact the inclined lever 14 swinging same upwardly until the inner end of the bushing comes to the marked point 14x on the lever 14. At this moment the reading of the pointer 8 on scale 2 is taken giving the desired measurement of intra-ocular pressure. If the pointer 8 at the time of reading is at position "0," the eyeball will be denoted as being very hard or subjected to undue intra-ocular pressure. The further the pointer swings away from "0" the softer is the eyeballs or the less the pressure. The tonometer however may if desired be applied in a vertical position to the eye of a patient while reclining on his back, in which case the lever 14 will be subjected to gravity so that the weight 15 will touch sleeve 5. This however presents no influence upon the measurement.

I do not limit my invention to the exact form shown in the drawing, for obviously changes may be made therein within the scope of the claims.

I claim:

1. A tonometer, comprising a plate having a scale; a pointer pivoted thereon and swingable over said scale; an arm on said pointer; a sleeve on said plate having a concave outer end shaped to the curvature of an eyeball; a pin slidable in said sleeve and having its inner end engaging said arm; the outer end of the pin normally projecting into said concave end of the sleeve; and means for adjusting the balance of the pointer when the plate is held in operative position.

2. In a tonometer as set forth in claim 1, said adjusting means comprising a lever on the said arm inclined in the direction of the pointer; and a shiftable weight on said lever.

3. A tonometer, comprising a plate having a scale; a pointer pivoted thereon and swingable over said scale; an arm on said pointer; a sleeve on said plate having a concave outer end shaped to the curvature of an eyeball; a pin slidable in said sleeve and having its inner end engaging said arm, the outer end of the pin normally projecting into said concave end of the sleeve; a bushing slidable on said sleeve; handles carried by said bushing whereby the tonometer may be supported and the bushing may be shifted towards the concave end of the sleeve; and means for controlling the force applied to the bushing in shifting the same during measurement.

4. In a tonometer as set forth in claim 3, said controlling means comprising a key on said sleeve

engaging a keyway in said bushing; a lever pivoted at the end of the key adjacent the concave end of the sleeve; means gravitationally maintaining the lever at an acute angle to the sleeve when the plate is in operative position; an adjustable weight on said lever; and said lever having an indicia thereon cooperating with the adjacent end of the bushing to denote the proper position of the bushing on the sleeve during its movement towards the concave end of the sleeve when the reading of the pointer on the scale should be taken.

5. In a tonometer as set forth in claim 3, said controlling means comprising a key on said sleeve engaging a keyway in said bushing, a lever pivoted at the end of the key adjacent the concave end of the sleeve; means gravitationally maintaining the lever at an acute angle to the sleeve when the plate is in operative position; an adjustable weight on said lever having a recess in its periphery conforming with the shape of the sleeve to permit the lever to swing towards the sleeve when the bushing slidably contacts the lever; and said lever having an indicia thereon cooperating with the adjacent end of the bushing to denote the proper position of the bushing on the sleeve during its movement towards the concave end of the sleeve when the reading of the pointer on the scale should be taken.

30 6. A tonometer, comprising a plate having a scale; a pointer pivoted thereon and swingable over said scale; an arm on said pointer; a sleeve on said plate having a concave outer end shaped to conform with the curvature of an eyeball; a pin slidable in said sleeve and having its inner end engaging said arm; the outer end of the pin normally projecting into said concave end of the sleeve; means for adjusting the balance of the pointer when the plate is held in operative position; a bushing slidable on said sleeve; handles carried by said bushing whereby the tonometer may be supported and the bushing may be shifted towards the concave end of the sleeve; and means for controlling the force applied to the bushing in shifting the same during measurement.

7. In a tonometer as set forth in claim 6, said adjusting means comprising a lever on the said arm inclined in the direction of the pointer; and a shiftable weight on said lever.

50 8. In a tonometer as set forth in claim 6, said controlling means comprising a key on said sleeve engaging a keyway in said bushing; a lever pivoted at the end of the key adjacent the concave end of the sleeve; means gravitationally maintaining the lever at an acute angle to the sleeve when the plate is in operative position; an adjustable weight on said lever; and said lever having an indicia thereon cooperating with the adjacent end of the bushing to denote the proper position of the bushing on the sleeve during its movement towards the concave end of the sleeve when the reading of the pointer on the scale should be taken.

65 9. In a tonometer as set forth in claim 6, said controlling means comprising a key on said sleeve engaging a key way in said bushing, a lever pivoted at the end of the key adjacent the concave end of the sleeve; means gravitationally maintaining the lever at an acute angle to the sleeve when the plate is in operative position; an adjustable weight on said lever having a recess in its periphery conforming with the shape of the sleeve to permit the lever to swing towards the sleeve when the bushing slidably contacts the

lever; and said lever having an indicia thereon cooperating with the adjacent end of the bushing to denote the proper position of the bushing on the sleeve during its movement towards the concave end of the sleeve when the reading of the pointer on the scale should be taken.

10. A tonometer, comprising a plate having a scale; a pointer pivotally mounted thereon and swingable over said scale; an arm extending laterally of said pointer; a sleeve having a bore offset from said pivot; a pin slidably mounted in said bore and having a head engaging said arm; the outer end of the sleeve having an enlargement coaxial with said bore provided with a concave outer face shaped to conform with the curvature of an eyeball; the outer end of the pin normally projecting into said concavity; means for adjusting the balance of the pointer when the plate is held in operative position; a bushing slidably mounted on said sleeve; handles carried by said bushing whereby the tonometer may be supported and the bushing may be shifted towards the enlargement of the sleeve; and means for controlling the force applied to the bushing in shifting the same during measurement.

11. In a tonometer as set forth in claim 10, said adjusting means comprising a lever on the said arm inclined in the direction of the pointer; and a shiftable weight on said lever.

12. In a tonometer as set forth in claim 10, said

controlling means comprising a key carried by said sleeve engaging a keyway in said bushing, a lever pivoted at the end of the key adjacent the enlargement; means normally maintaining the lever at an acute angle to the sleeve when the plate is in operative position; an adjustable weight on said lever; and said lever having an indicia thereon cooperating with the adjacent end of the bushing to denote the proper position of the bushing on the sleeve during its movement towards the enlargement when the reading of the pointer on the scale should be taken.

13. In a tonometer as set forth in claim 10, said controlling means comprising a key carried by said sleeve engaging a keyway in said bushing, a lever pivoted at the end of the key adjacent the enlargement; means normally maintaining the lever at an acute angle to the sleeve when the plate is in operative position; an adjustable weight on said lever having a recess in its periphery conforming with the shape of the sleeve to permit the lever to swing towards the sleeve when the bushing slidably contacts the lever; and said lever having an indicia thereon cooperating with the adjacent end of the bushing to denote the proper position of the bushing on the sleeve during its movement towards the enlargement when the reading of the pointer should be taken.
